UNITED STATES PATENT OFFICE

163,774

POT AND PAN SCRAPER

Alfred J. C. Schwartz, Evanston, Ill.

Application July 10, 1950, Serial No. 11,034

Term of patent 7 years

(Cl. D9—6)

To all whom it may concern:

Be it known that I, Alfred J. C. Schwartz, a citizen of the United States of America, residing at Evanston, in the county of Cook and State of Illinois, have invented a new, original, and ornamental Design for a Pot and Pan Scraper, of which the following is a specification, reference being had to the accompanying drawing, forming a part hereof.

In the drawing:

I claim:

The ornamental design for a pot and pan scraper, as shown.

ALFRED J. C. SCHWARTZ.
